Seward Davis

UNITED STATES PATENT OFFICE.

WILLIAM Y. DEAR, OF JERSEY CITY, NEW JERSEY.

CALENDAR-PAD AND MOUNT THEREFOR.

1,396,814.

Specification of Letters Patent.

Patented Nov. 15, 1921.

Application filed June 28, 1921. Serial No. 481,094.

To all whom it may concern:

Be it known that I, WILLIAM Y. DEAR, a citizen of the United States of America, and a resident of the city of Jersey City, in the 5 county of Hudson and State of New Jersey, have invented certain new and useful Improvements in Calendar-Pads and Mounts Therefor, of which the following is a full, clear, and exact description, reference being 10 had to the accompanying drawings, forming a part of this specification.

The objects of my invention are to provide a calendar in padded form mounted securely upon and firmly held by a metallic reinforce, 15 which reinforce may be readily bent manually to form a stand for the pad so that it will be supported on a horizontal surface in an inclined position, and which reinforce, prior to such bending, shall fit snugly about 20 the pad so as not to add materially to the dimensions of the pad, save by the thickness of the metal, and thereby to permit its shipment as a rectangular package without increased bulk. Further objects are to afford 25 a mount which may be manufactured by a single stamping and bending operation from comparatively thin sheet metal and yet be of ample strength to maintain the pad in its inclined position with sufficient rigidity to 30 support it while being written upon. Further desired features of advantage and utility are attained by the construction hereinafter described, as will be made apparent.

With these objects in view, my invention 35 consists in stamping from a sheet of metal of approximately No. 28 gage, a substantially T-form reinforce; at the same operation, cutting two oppositely disposed tangs in the horizontal arms of the reinforce adapted to 40 be bent up and to be inserted through the thickness of a calendar pad; in bending up said tangs and also two lateral flanges at the extremities of the arms to embrace the sides of the pad; in scoring two lines across these 45 arms adjacent the tang-bases, and also in impressing a hairpin-shaped rib in the vertical leg of the reinforce, all at the one operation by suitably formed dies. My invention further consists in the mounting of a calendar pad upon said reinforce so as to constitute it a rectangular package substantially 50 of the dimensions of the pad itself and adapted for shipment without increased bulk or risk of injury. Finally, my invention consists in the provision of such a calendar pad

and mount as described, capable of ready adjustment by the user so as to constitute said mount as a support when the horizontal arms are bent back along the scored lines, an operation easily performed by reason of the reduction of the metal by the cutting out of the prongs. When bent back from the pad, at right angles thereto, the flanges form a pair of feet for the legs thus formed, and, with the vertical portion of the T, a tripod support results. The vertical portion of the T reinforces the length of the pad and by virtue of the stiffening rib formed therein, maintains the pad flat against pressure, as by writing thereon.

In the accompanying drawings forming a part of this specification, the invention is illustrated in its preferred structural embodiment, in which drawings Figure 1 is a plan view of the metallic reinforce as 75 stamped; Fig. 2 is a perspective view of the reinforce as bent for application to the pad; Fig. 3 is a view in horizontal elevation of a pad with the reinforce applied thereto and ready for packaging for shipment, underlying parts being shown in dotted outline; Fig. 4 is a perspective view of the reinforce removed from the pad to permit illustration of the method of bending manually for use as a stand; and Fig. 5 is a view similar to 80 Fig. 3, but showing the amount as bent in Fig. 4 to form a stand.

Like reference characters indicate like parts throughout the several figures, in which 90 1 is the vertical element of the T-shaped mount; 2 is one of the horizontal arms having the end 3 adapted to upward bending upon the line 4 to form a flange. 5 is a prong adapted to be bent upward to form a pad-penetrating means; 6 is an element 95 adapted to form a leg; 9 is a stiffening bead of inverted U-shape. 10 is a pad to which the reinforcing mount has been applied. As clearly shown, two prongs and two flanges 100 symmetrically disposed are formed, one set at each side of the median prolongation of the vertical element of the reinforcing mount, the metal whereof is preferably weakened on the lines 4 and 7 to facilitate its being bent. The manual bending of the 105 lug-footed legs 6 is further facilitated by the cut-away portion forming the prong base.

Having thus described my invention, which is susceptible of modification and variations 110

without departure from the spirit of my disclosure thereof, I claim:

1. In a mount for calendar pads, a one-piece metallic reinforce having upwardly bent prongs adapted to penetrate said pad, a pair of upturned lugs adapted to embrace said pad during shipment and to be bent downwardly to constitute supports therefor when in use, and a backing adapted to afford 10 a third support.

2. As an article of manufacture, a metallic blank of substantially T-shape having a stiffening bead in the vertical member, two portions of the horizontal members being 15 adapted to be projected as prongs from the plane of the horizontal members, and a weakening of the metal on lines across the horizontal members on each side of the extension forming the vertical member, and adjacent and substantially parallel to the bases 20

of the prongs, said weakening of the metal being adapted to facilitate bending thereof manually to form offset supports.

3. A calendar-pad mount consisting of a metallic reinforce adapted to engage three 25 sides of said pad, and constituting a protective holder conformed thereto, the said mount comprising two elements adapted to be bent downwardly from the third element and to afford with the third element a tripod 30 support for said pad when in use, the two downwardly bent elements being adapted to be bent again at right angles to themselves to form feet for said elements, the metal being weakened to facilitate and guide the several 35 bendings, said mount further comprising two prongs projected upwardly from the plane of the third element and adapted to fix the pad thereon

WILLIAM Y. DEAR.
